(57) **CLAIM**

The ornamental design for a temperature controller housing, as shown and described.

DESCRIPTION

FIG. 1 is a perspective view of a temperature controller housing;

FIG. 2 is front view of the temperature controller housing of FIG. 1;

FIG. 3 is back view of the temperature controller housing of FIG. 1; and,

FIGS. 4-7 are left, right, top and bottom views of the temperature controller housing of FIG. 1.

The portions illustrated in broken lines on the figures are for illustrative purposes only and form no part of the claimed design.
